UNITED STATES PATENT OFFICE.

ROY V. COLLINS, OF NEWTON, MASSACHUSETTS, ASSIGNOR TO THE WEST NEWTON COMPANY, OF WEST NEWTON, MASSACHUSETTS, A CORPORATION OF MASSACHUSETTS.

CONTACTOR.

1,322,879.

Specification of Letters Patent.

Patented Nov. 25, 1919.

Application filed November 15, 1915. Serial No. 61,493.

To all whom it may concern:

Be it known that I, Roy V. Collins, a citizen of the United States, residing at Newton, county of Middlesex, State of Massachusetts, have invented an Improvement in Contactors, of which the following description, in connection with the accompanying drawing, is a specification, like characters on the drawing representing like parts.

This invention relates to contactors such as are used in connection with the trolley wire in an electric block signal system for closing a circuit of the signal system whenever the trolley of an electric car passes by the contactor during the movement of the car, and particularly to contactors of that type in which the trolley wire is secured to a contact-actuating member, which in turn is movably mounted in a supporting member that is carried by the usual span wires, and a spring is interposed between the actuating member and the supporting member, which spring normally has insufficient strength to support the weight of the trolley wire. In contactors of this type the weight of the trolley wire holds normally the actuating member in its lowermost position, but when a trolley passes along under the trolley wire, the lifting force of the trolley helps to sustain the trolley wire and relieves the spring of the contactor of sufficient weight so that said spring operates to move the actuating member relative to the casing, this movement being made use of to close the contact of the signaling circuit.

Among the objects of the invention are to provide a contactor of this type having novel circuit-closing means by which two contacts will be made successively and in a predetermined time interval or a contact may be made and broken in a predetermined time relation regardless of the speed at which the trolley may be moving along the trolley wire, and otherwise to improve contactors of this type, all as will be more fully hereinafter set forth.

In order to give an understanding of my invention, I have illustrated in the drawings a selected embodiment thereof which will now be described, after which the novel features will be pointed out in the appended claims.

Figure 1 is a side view of a contactor em-

bodying my invention, said figure showing 55 the device partly in section;

Fig. 2 is an end view of Fig. 1.

1 indicates a portion of the trolley wire which is secured to the usual shoe or ear 2 by which it is suspended. My improved contactor is associated with the suspending means for the wire, and it comprises a supporting member or casing 3 herein shown as provided with ears 4 to which the usual span wires 5 are secured. The shoe or ear 2 is suspended from the supporting member 3 through an actuating member 6 which is provided with means to limit the downward movement of the actuating member relative to the casing. In the construction herein shown, this actuating member is provided with a head 7 which is adapted to rest on a shoulder 8 formed in the casing so that when the parts are in the normal position, the weight of the trolley wire is transmitted to 70

the casing 3 through the actuating member 6, head 7 and shoulder 8. 9 designates a spring which surrounds the actuating member 6 and bears at its upper end against the head 7 and at its lower end against a collar 80

10. This spring 9 has a strength insufficient to support the weight of the trolley wire 1 and shoe 2, so that under normal conditions, the head 7 will rest against the shoulder 8. When the trolley passes underneath the 85

trolley wire, the upward pressure of the trolley against the wire will sustain part of the weight of the latter. The tension or strength of the spring 9 is so adjusted that said spring will support the portion of the 90

weight of the trolley wire which is not sustained by the passing trolley. To illustrate, if it is assumed that the weight of the trolley wire at the contactor is forty pounds and the spring 9 is adjusted to sustain thirty pounds 95

only, it will be seen that the forty-pound weight will overcome the thirty pounds pressure of the spring so that the head 7 will seat against the shoulder 8. If, however, the passing trolley provides an upward pressure against the trolley wire of fifteen pounds, then the spring 9 will more than balance 100

the remaining weight of the trolley wire and will move the actuator 6 upwardly relative to the casing 3. As soon as the trolley passes and the full weight of the trolley wire comes on the actuator 6, the parts will return to the position shown in Fig. 1.

This upward movement of the actuating member 6 relative to the supporting member 3 is made use of to close the contact of the signaling circuit, as will be presently described.

One of the features of my invention relates to the provision of adjusting the tension of the spring 9 so as to give it a load-supporting power having the proper relation to the weight of the trolley wire. In order that the device may operate properly, it is essential that the resistance or strength of the spring 9 be a predetermined proportion of the entire weight of the trolley wire, for if the spring has a fixed resistance and there should be any change in the weight of the trolley wire, then the spring would not properly operate. I have provided a spring which is capable of adjustment by making the collar 10 adjustable in the casing 3. This can easily be accomplished by merely screw-threading the collar into the casing, as shown. The adjusting of the collar up or down will vary the resisting power of the spring, and this construction makes it possible to adjust the spring to the proper tension after the device is installed and the weight of the trolley wire is determined.

The particular form of contact which is closed by the actuating member 6 may vary and will depend somewhat on the character of the signal system with which the device is used. A simple construction is herein shown in which the actuating member 6 is provided at its upper end with two arms or projections 13 and 14 between which is received a contact member 11 pivoted to the supporting member 3 at 12, and which I will refer to as a circuit-closing contact. This circuit-closing contact is constructed to close the contacts of the circuit when it is moved upwardly by the actuating member 6. The movement of the circuit-closing contact member 11 may be used simply to close a single circuit, or may be used to close a plurality of circuits, or to open one circuit and close another, depending on the character of the signal system with which the device is used. In the illustrated embodiment of my invention, the upward movement of the contact member 11 is arranged to close two circuits in succession and in predetermined timed relation, regardless of the speed at which the actuating member 6 is moved.

15 and 16 indicate two spring contacts which are suitably secured to a stand 17 rising from the supporting member 3, said contacts 15 and 16 being insulated from the stand and connected to the circuit wires 18 and 19 leading to the signal mechanism. Each contact is provided with the V-shaped nose or end, the V-shaped end of the contact 15 being indicated at 20, and that of the contact 16 at 21. The end 20 is provided with the section 22 of insulation on one side of the

V, and the end 22 is similarly provided with a section of insulation 23 on the opposite side of the V. These contacts are arranged closely adjacent to each other, but are insulated from each other and are normally situated so that the end of the circuit-closing contact member 11 lies below the V-shaped end 20 of the member 15. The circuit-closing contact member 11 is in electrical connection with the trolley wire 1 and when it is swung upwardly by the upward movement of the actuator 6, it will come in contact and wipe over the insulated portion 22 of the contact 15, thereby forcing the contact 15 backwardly. As the contact 11 passes the apex of the end 20 and moves down the side 25 of the V, the circuit 18 will be closed through the contact 15 and contact 11. As soon as the contact 11 passes the apex of the end 20, the resiliency of the contact 15 will tend to move it forwardly, thus forcing the contact member 11 down the incline 25 and into engagement with the inclined face 26 of the contact 16. When the contact element engages the face 26 of the contact 16, then the circuit 19 will be connected to the trolley wire through the contacts 11 and 16. The projections 13 and 14 are sufficiently separated so as to allow the contact 11 to have a certain amount of loose play, and as a result, when the contact 11 passes the apex of the end 20, the resiliency of the contact 15 will cause said contact 11 to move rapidly down the inclined face 25 into engagement with the face 26, thus successively closing the circuits 18 and 19. The loose play provided for the contact 11 between the projections 13 and 14 permits this rapid movement of the contact element down the surface 25 and onto the surface 26, regardless of the speed at which the actuator 6 is moving, and the two circuits 18 and 19 will, therefore, be always closed successively and in predetermined timed relation without regard to the speed at which the actuator is being operated.

It sometimes happens that the trolley wire will be given a longitudinal movement relative to the contactor due to unequal expansion or contraction of the wire or unequal tension therein. In order to provide for such longitudinal movement of the trolley wire without affecting the operation of the contactor, I propose to provide a connection between the ear or shoe 2 and the actuating member 6 which will permit of such longitudinal movement of the wire. The actuator 6 is shown as provided at its lower end with a forked head 28, between the forks of which is a head 29 of a connection 30 that is screwed into the ear 2. This head 29 is provided with an elongated slot 31 in which is received a pin 32 carried by the forked head 28. This pin-and-slot connection permits longitudinal movement of the trolley wire

without interfering with the normal operation of the device.

While the construction herein shown is one adapted to close two circuits in predetermined time relation, yet it will be obvious that the same mechanism might be used for opening one circuit and then closing another circuit in predetermined relation, this involving nothing more than ordinary wiring changes.

Further, it will be understood that while I have illustrated a selected embodiment of my invention I do not wish to be limited to the constructional features shown.

15 I claim:

1. In a contactor, the combination with a supporting member having means for suspending it, of an actuating member movably sustained by the supporting member 20 and from which the trolley wire is sustained, said actuating member having two opposed projections, a spring interposed between the actuating member and the supporting member, a contact member secured to the supporting member, and a second contact member pivoted to the supporting member and extending between said projections.

2. In a contactor, the combination with a supporting member having means for suspending it, of an actuating member movably mounted in the contact member and from which the trolley wire is sustained, said actuating member having two opposed projections, a spring interposed between the 35 supporting member and the actuating member, two contact members secured to the supporting member, a circuit-closing contact pivotally connected to the supporting member and extending between said projections, 40 said two contact members being situated so that movement of the actuator causes the circuit-closing contact to engage them successively.

3. In a contactor, the combination with a 45 supporting member, of an actuating member movably mounted in the supporting member, a spring interposed between the actuating member and the supporting mem-

ber, two contacts carried by the supporting member, a circuit-closing contact actuated 50 by movement of the actuating member relative to the supporting member and adapted to engage the two contacts successively.

4. In a contactor, the combination with a trolley wire, of two contact members associated therewith, a circuit-closing contact, and means rendered operative by a trolley passing over the trolley wire to move said circuit-closing contact into engagement with the contact members successively in a predetermined time relation.

5. In a contactor, the combination with a supporting member, of a trolley wire suspended therefrom, two contact members connected to separate circuits, a circuit-closing contact, and means rendered operative by a trolley passing over the trolley wire to move said circuit-closing contact into engagement with the contacts successively and in a predetermined time relation.

6. In a contactor, the combination with a supporting member, of an actuating member movably sustained therein, a trolley wire suspended from the actuating member, two contact members connected to separate circuits, a circuit-closing contact actuated by the actuating member, and means for closing said circuit-closing contact to engage the two contact members successively and in predetermined time relation regardless of 75 the speed at which the trolley is moving.

7. In a contactor, the combination with a supporting member, of a trolley wire suspended therefrom, two contact members connected to separate circuits, a circuit-closing contact, means rendered operative by a trolley passing over the trolley wire to move said circuit-closing contact from one of said contact members to the other in a predetermined time relation regardless of the speed 90 at which the trolley is passing along the wire.

In testimony whereof, I have signed my name to this specification.

ROY V. COLLINS.
